AIR CONDITIONING SYSTEM FOR
BUILDINGS

Frederick C. Cowderoy-Dale, Dallas, Tex.

Application April 12, 1937, Serial No. 136,360

4 Claims. (Cl. 98—33)

This invention relates to new and useful improvements in air conditioning systems for buildings.

One object of the invention is to provide an improved system for efficiently conditioning and circulating air through a building structure, said system being most economical to install and operate and being adapted for use throughout the year, being constructed to cool the air in the summer and to heat the air in the winter.

An important object of the invention is to provide an improved air conditioning system for a building, wherein a central conditioning chamber is formed beneath the building and is constantly supplied with fresh air, with means for conducting the conditioned air to the various rooms of said building, whereby an effective circulation of the conditioned air throughout the structure is had; there being no return of air from the building to the central chamber, whereby only fresh air is supplied at all times to said chamber.

Another object of the invention is to provide an improved means for cooling air to be circulated through a building, wherein a conditioning chamber is located underground beneath the building with means for supplying fresh air to the chamber; the fresh air being cooled by evaporation of water in the underground chamber and ducts and then circulated through the building, the warm air within the building escaping therefrom through vents in the roof.

A further object of the invention is to provide an improved system for heating air to be circulated throughout a building wherein fresh air is supplied to a central underground chamber and is heated therein after which it is conducted through the building to heat the same.

Still another object of the invention is to provide an air conditioning system for a building having a central room having a substantially circular shape with the remaining rooms of the building being located around said central room, whereby it is possible to locate a central air conditioning chamber beneath the central room and efficiently conduct conditioned air to all of the rooms of the building.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is a vertical sectional view of a building having an air conditioning system constructed in accordance with the invention, and

Figure 2 is a floor plan of the building.

In the drawing, the numeral 10 designates a central room of a building which is substantially octagonal in shape. As clearly shown in Figure 2, the other rooms 11, 12 and 13, as well as the room 14, are disposed around this central room. Suitable doorways (not shown) establish communication between the central room and the other rooms of the building and with the floor plan shown, a most compact building is had. It is preferable that the improved air conditioning system be applied to this type of building although it is not essential, as it may be utilized to condition the air of any structure.

A central air conditioning chamber or basement 15 is formed beneath the central room 10 of the building and as shown, this chamber is entirely underground. A fresh air duct or supply conduit 16 leads from the chamber and extends beneath the outer room 12 of the building to a sump or reservoir 17 which is located adjacent the outer wall of the building. The upper end of the sump is open to the atmosphere to permit fresh air to enter the conduit or duct 16 and chamber 15, and the walls of said sump extend above the ground level A, whereby water cannot drain thereinto. A suitable grill 18 covers the open end of the sump to prevent extraneous matter from falling thereinto, while a suitable duct screen 19 is disposed at each end of the duct 16. Thus, it will be obvious that outside fresh air may enter the duct and flow into the conditioning chamber 15.

For drawing the fresh air into the chamber 15, a suitable fan 20 is mounted in the inlet end of the duct 16 and acts to force fresh air into said chamber.

During the summer when the system is used for cooling the air within the building, it is necessary to cool the air entering the chamber and for this purpose, a water pipe 22 extends throughout the length of the duct 16 above the same. This pipe has a plurality of nozzles whereby water may drip down into the duct to keep the bottom of the same wet at all times. The conduit is slightly inclined downwardly toward the chamber 15 to permit the water therein to drain onto the floor of said chamber. One end of the pipe overhangs the sump and has a faucet or pet cock 23 therein, whereby water may be introduced into the bottom of the sump which

depends below the outlet end of the duct, as is clearly shown in Figure 1.

The opposite end of the water pipe 22 extends into the chamber or basement 15 and has an outlet nozzle 24 connected therein, whereby water constantly drips onto the floor of the chamber, and manifestly, the floor is damp or wet at all times during summer operation.

The fresh air which is drawn in from the outside by the fan 20 enters the sump and flows through the conduit or duct 16. In its passage, this air contacts the water standing in the sump 17 and also the wet bottom of the duct and is thereby cooled by evaporation by said water. Upon entering the chamber 15, the air contacts the wet floor of said chamber or basement and is further cooled. Of course, since the chamber is underground its temperature is much cooler than the temperature above ground so that further cooling of the incoming air is affected by a heat exchange.

For conducting the cooled air from the basement or chamber 15, a plurality of registers or outlets 25 are mounted in the wall of said chamber near the floor thereof. These registers may be of the usual construction and may be purchased on the open market. Each register is provided with the usual shutter (not shown) or other closure means, whereby said register may be closed. Leading upwardly from each register is a flue or conduit 26 which is located in the wall of the building and the upper end of this flue communicates with a wall register 27 which is mounted in the wall of the various rooms near the ceiling thereof. The registers 21 may or may not be provided with shutters, as desired. Any desired number of flues 26 may be provided for each room but only one for each has been shown.

Manifestly, the fresh air which is cooled in traveling through the inlet duct 16 and in entering the basement, is conducted upwardly through the registers 25 and flues 26 and escapes through the registers 27 into the rooms of the building. It is noted that the cool air enters each room near the ceiling and will tend to flow toward the floor. The hot air in the room will of course, rise toward the ceiling and escapes therefrom through a vent 28 provided in the roof of the building, whereby the hot air escapes to the atmosphere. The flow of air through the vent is controlled by a pivoted damper 29 which may be operated by a suitable mechanism (not shown) from within the room. Thus, cool fresh air is supplied at all times to the rooms of the building while the warm air within said rooms is constantly escaping through the vents 28, whereby a constant circulation within each room is set up. No refrigerating unit is required and the cost of operation of the unit for cooling the building is practically nil. The original cost of installation of the equipment is very low as the number of parts are minimized and no specially constructed equipment is required.

From the above, it will be seen that an efficient system for summer operation for cooling the fresh air is provided. When it is desired to heat the building during winter operation, the fresh air is drawn into the chamber or basement 15 through the sump 17 and duct 16 by the fan 20. The water pipe nozzles are regulated so as to moisten or dampen the air but it is not necessary to saturate this incoming air, as is done in summer operation. This moistened air enters the chamber 15 and is heated therein by a suitable

furnace or heater 30, which holds the temperature of the air within the chamber at a predetermined point. Of course, as the cool outside air enters the chamber, it admixes with the warm air therein and is heated. The inlet of cold outside air may be regulated by a damper 17 located at the upper end of the sump 17.

Since the hot air tends to rise it is not practical to introduce the same into the rooms of the building through the registers 25 and flues 26, so the registers 25 are closed during winter operation to prevent the escape of the hot air through the flues 26. To conduct the heated air to the rooms, a plurality of registers 31 are mounted in the wall of the chamber or basement 15 near the ceiling of said chamber and these registers are connected by conduits 32 with registers 33 mounted in the walls of the various rooms. Each of the latter registers is located in the wall of room at the floor thereof, whereby the hot air entering the room rises therein to thoroughly heat the same. By moistening the fresh air, the air is conditioned so as to make for increased comfort to the occupants of the building. During the winter operation, the dampers 29 are properly adjusted so as to control the escape of air from the rooms. It is desirable that they be slightly open to provide for a constant circulation of fresh air through the rooms of the building.

The entire system is most economical to install and operate and may be easily changed from winter to summer operation or vice versa. As above stated, the registers 25 are closed during the winter operation to allow supply of air to the rooms through the registers 33 and similarly, during summer operation the registers 33 are closed to permit air to be supplied through the registers 25 and 27. It is pointed out that while only one fresh air inlet duct is shown a plurality of such ducts may be used to conduct the fresh air into the central condition chamber or basement of the building. Although the system has been shown in a particular structure, it is evident that it may be applied to any type of house, or other building.

What I claim and desire to secure by Letters Patent is:

1. An air conditioning system for a building including, a central air chamber beneath said building, means for supplying fresh outside air to the chamber, means for cooling the air entering the chamber, means within the chamber for heating the air therein, a conductor communicating with the lower portion of the chamber for conducting the cooled air to the interior of the building, a second conductor communicating with the upper end of the chamber for conducting heated air from the chamber to the interior of the building, means for closing the first named conductor when the heating means is operating, and means for closing the other conductor when the air in the chamber is being cooled.

2. An air conditioning system for a building including, a central air chamber beneath said building, means for supplying fresh outside air to the chamber, means for cooling the air entering the chamber, means within the chamber for heating the air therein, a conductor communicating with the lower portion of the chamber for conducting the cooled air to the interior of the building, a second conductor communicating with the upper end of the chamber for conducting heated air from the chamber to the interior of the building, means for closing the first named conductor when the heating means is operating,

means for closing the other conductor when the air in the chamber is being cooled, and a vent in the roof of the building for creating a constant circulation of air through the interior of the building without recirculating the air from the interior through the conditioning chamber.

3. An air conditioning system for a building including, a central air chamber beneath said building, a duct for supplying fresh outside air to the chamber, means for cooling the air entering the chamber, means within the chamber for heating the air therein, a conductor communicating with the lower portion of the chamber for conducting the cooled air to the interior of the building, a second conductor communicating with the upper end of the chamber for conducting heated air from the chamber to the interior of the building, means for closing the first named conductor when the heating means is operat-

ing, and means for closing the other conductor when the air in the chamber is being cooled.

4. An air conditioning system for a building including, a central air chamber beneath said building, a duct for supplying fresh outside air to the chamber, means within the duct for moistening the fresh air, means for cooling the air entering the chamber, means within the chamber for heating the air therein, a conductor communicating with the lower portion of the chamber for conducting the cooled air to the interior of the building, a second conductor communicating with the upper end of the chamber for conducting heated air from the chamber to the interior of the building, means for closing the first named conductor when the heating means is operating, and means for closing the other conductor when the air in the chamber is being cooled.

FREDERICK C. COWDEROY-DALE.
